Attorney

UNITED STATES PATENT OFFICE.

FRANK MADLE, OF BURWYN, ILLINOIS, ASSIGNOR TO CRUVER MANUFACTURING COMPANY, OF CHICAGO, ILLINOIS, A CORPORATION OF ILLINOIS.

TOY WHISTLE.

Application filed April 20, 1925. Serial No. 24,546.

This invention has for its object to provide a very cheap and simple toy whistle including a cylindrical body providing a large surface adapted to contain advertising matter and which, furthermore, may, by closing or partially closing the outer open end of the housing, be caused to produce different notes or tones.

The preferred embodiment of the invention is illustrated in the accompanying drawings, wherein:

Fig. 1 is a perspective view of a whistle constructed in accordance with the invention.

Fig. 2 is a plan view of the same.

Fig. 3 is a view similar to Fig. 2 showing the body of greater length.

Figs. 4 and 5 are, respectively, sectional views on the line 4-4 and 5-5 of Fig. 2.

The device comprises a cylindrical body 1 which may be varied in length for varying the tones produced thereby and varying the surface area adapted to be devoted to advertising matter. The body portion 1 is hollow and open at each end. Formed integral with the inner end of the body portion 1 is a semicylindrical extension 2 disposed lengthwise with respect to the latter and which is folded upon itself, intermediate its ends, to provide a tongue 3 extending lengthwise with respect to the body portion and further projecting a substantial distance within the latter. The tongue is spaced throughout from the top portion of the inner face of the body portion 1, and is constructed in a manner whereby the free end thereof will converge slightly towards the said portion of said inner face.

The outer portion of the projection 2, the tongue 3 and the bend 4 between said outer portion and tongue are cut away to provide an opening 5 which extends lengthwise of the bend 4 and transversely of the tongue 3 and said outer portion. Said opening 5 in side elevation is semi-oval in contour.

The outer portion of the projection 2, in connection with the tongue 3 provides a lip piece for directing a blast of air through the opening 5 into the body portion 1. The blast passes between the tongue and that portion of the inner face of the body portion 1 towards which the tongue converges.

In the top of the body 1 adjacent said extension 2 there is a perforation 6 of semi-circular form, the arcuate wall of which is

opposed to the space between the tongue 3 and the upper wall and in the path of the blast of air projected through the perforation 5, the impingement of said blast against the thin edge afforded by said arcuate wall 60 causing the vibration resulting in the sound commonly designated as whistling.

If the outer end of the body is entirely unobstructed when the blast of air is projected through the perforation 5, the whistle 65 will be very shrill and become deeper toned as the outer end of the body is gradually obstructed until no air may pass therefrom. The device is thus rendered attractive as a more or less musical toy of a very cheap 70 type.

I claim as my invention:

1. A toy whistle comprising a substantially cylindrical housing open at both ends and provided between its ends with an opening, 75 a semi-cylindrical extension projecting from the top of said housing at its inner end and disposed lengthwise thereof, said extension bent upon itself intermediate its ends to provide a tongue disposed lengthwise of and extending a substantial distance within said housing, said tongue spaced from and arranged in close proximity to the top of the inner face of said housing, the bend in said extension formed with an opening, a wall 80 of said first-named opening being positioned to be in the path of a blast of air projected through the second named opening.

2. A toy whistle comprising a substantially cylindrical housing open at both ends and provided between its ends with a substantially semi-circular opening, a semi-cylindrical extension projecting from the top of said housing at its inner end and disposed lengthwise thereof, said extension bent upon itself intermediate its ends to provide a tongue disposed lengthwise of and extending a substantial distance within said housing, said tongue spaced from and arranged in close proximity to the top of the inner face 90 of said housing, the bend in said extension formed with a lengthwise extending opening, the free end of said tongue converging towards the top of the inner face of the housing, the arcuate wall of said first-named opening being positioned to lie in the path 95 of a blast of air projected through the second named opening.

105

FRANK MADLE.
